CARRIER FREQUENCY SYSTEM

Wolfgang Hagen, Berlin, Germany; vested in
the Alien Property CustodianApplication October 10, 1941, Serial No. 414,415
In Germany March 28, 1940

3 Claims. (Cl. 179—15)

This invention relates to carrier frequency systems of the kind in which two or more wave transmission channels are used.

In prior systems of this type wave filters are arranged to separate each channel from the other channel and also to separate each direction of conversation from the other direction. This entails a large expenditure in filters.

In arrangements as provided by the invention, one intercommunication band is based on a carrier the lower side-band of which is used for one direction of conversation while the upper side-band is employed for the other direction. Further, as regards a second intercommunication band, one direction of conversation thereof is created by means of the upper side-band of a second carrier while for the second direction the lower side-band of a third carrier frequency or both side-bands thereof are used.

In the drawing, Fig. 1 illustrates a frequency distribution suitable for carrying out the invention, Fig. 2 graphically represents a filter arrangement for this frequency distribution, Fig. 3 is a circuit diagram in which such filter arrangement is included, Figs. 4 and 5 are graphs referred to in explaining the function of arrangements as provided by the invention.

In Fig. 2, the frequency condition of the several transmission channels can be seen. Figs. 1 and 2 illustrate that one conversation, which may be designated as "lower" conversation, is transmitted with the aid of a carrier $Tr_1=5\text{kHz}$, that is 5 kilocycles per second. As regards the directions of this conversation, direction BA thereof is transmitted by the lower side-band K_1 while the other or opposite direction, namely AB, is transmitted by the upper side-band K_2 . The "upper" conversation is transmitted with the aid of the carrier frequencies

$$Tr_2=7.5\text{kHz} \text{ and } Tr_3=12.5\text{kHz}$$

In the direction AB of this conversation, the transmission is effected by the upper side-band K_3 of the carrier Tr_2 while in direction BA the transmission is by means of the lower side-band K_4 or by both side-bands of the carrier Tr_3 .

The frequency distribution so obtained results in an expenditure of wave filters which is less than has been the case heretofore. The channels K_2 , K_3 are both of the same direction. The filters TP_1 and $HP_7, 8$, Figs. 2 and 3, hence have to cut off the cross-talk attenuation only. By transmitting in the same direction no appreciable level differences between the two channels will occur. Also no filter need be arranged be-

tween the channels K_3 , K_4 of the upper conversation since the incoming low frequency arriving at NF_1 and NF_2 is limited by low-pass filters TP_2 and the carriers are suppressed by the modulating arrangement. The lower side-band of channel K_3 is suppressed by the separating filter $HP_1, 8$ which is effective between the two conversations. The upper channel K_4 may be employed for transmitting both side-bands. This will be of advantage as regards efficiency. The line attenuation increasing in accordance with higher frequencies requires an increased transmitting power to be employed and in its turn acts in a manner similar to a low-pass filter.

If, however, in the case of special lines still other carrier frequencies are to be transmitted simultaneously then the attenuation of these lines should not greatly increase with higher frequencies. In this case it is advantageous to cut off the upper side-band of Tr_3 from the lower side-band K_4 in order not to render the used frequency band wider than it must be. This expedient purposely renounces the greatest efficiency and may do so since the transmitting power of one side-band, namely of K_4 , is quite sufficient. A low-pass filter $TP12.2\text{kHz}$ may be provided for this purpose.

Fig. 4 shows the frequency distribution and the curve of line attenuation in the case of a simple two-way intercommunication, while Fig. 5 illustrates a frequency distribution suitable in cases where additional carrier frequencies belonging to another system are to be transmitted over the same line.

The direction of transmission of the upper conversation includes a modulator M and is accommodated to the line. The call receiving apparatus R is connected by high ohmic resistances in a manner to avoid loss of transmitting energy.

Otherwise such loss would occur since the receiving side is connected in parallel with the transmitting side.

In order to choose the directions of conversation a changeover switch S_1, S_2, S_3 is provided. In the case of the lower conversation the filters $HP5.3$ and $TP4.7$ are switched over at contacts S_2, S_3 while in the case of the upper conversation the carrier frequencies Tr_2 and Tr_3 are interchanged at contacts S_1 . The switching-over operation is effected with respect to the upper and lower conversations at the same time and in such a manner that the channels located in the middle and which correspond to the reference numerals 2, 3 always operate in the same direction. The two terminal stations may hence be made

similar to each other, and by means of switch S₁, S₂, S₃, they may be adjusted to suit frequency conditions.

A low frequency line NF may be connected to the outgoing line over a low pass filter.

What is claimed is:

1. A carrier frequency system comprising means to produce three different carriers, a transmission line, means to produce from each carrier a lower side-band and an upper side-band, means for transmitting one direction of a conversation over said line through the lower side-band of one of said carriers while transmitting the other direction thereof over said line by the upper side-band of the same carrier, and means for transmitting one direction of another conversation over said line through the upper side-band of a second carrier while transmitting the other direction thereof over said line by at least the lower side-band of the third carrier.

2. A system as defined in claim 1 and which comprises terminal stations similar to each other, wave filters, means to interchange these filters and thereby to interchange the directions of the conversation transmitted with the aid of a lower carrier frequency, and means to interchange the carriers and thereby to interchange the directions of the conversation transmitted by an upper carrier frequency.

3. A system as defined in claim 1 and which comprises a transmission channel of lower carrier frequency, a transmission channel of upper carrier frequency, and two transmission channels of carrier frequencies between the two said frequencies, these two channels being of the same direction while the two former channels are both of a direction which is the reverse of the latter direction.
